CAM-CLOSED, SLIDABLE JAW SOCKET WRENCH

George J. Bruhn, Grand Haven, Mich.

Application March 20, 1957, Serial No. 647,260

5 Claims. (Cl. 81—128)

This invention relates to a wrench and more particularly to an adjustable socket wrench that is adapted to be used on various size nut and bolt heads.

Several types of adjustable socket wrenches have been developed. To my knowledge, however, none of them have been completely satisfactory as evidenced by lack of commercial success. One type of adjustable socket wrench is disclosed in Patent No. 2,582,444. This type of wrench is adjustable by a collar having a cammed surface bearing against a plurality of jaws. Rotation of the collar causes the jaws to be moved inwardly or outwardly adapting the wrench to different size nuts. Another wrench of this type is disclosed in Patent No. 877,773 which has a cammed plate with a plurality of cammed slots which when the plate is rotated position the jaws.

Disclosures of this type have been available for some time, however, to my knowledge no commercially successful adjustable wrench has yet reached the market. The reason for this is believed to be the lack of a construction providing a means for rigidly supporting the jaws and still permitting the jaws to be adjusted.

An object of this invention is to solve this problem by providing a construction of an adjustable wrench which positively supports the jaws and provides a very sturdy and lasting apparatus.

Another object of this invention is to provide an adjustable wrench that is easily adjustable from the exterior of the socket but which still provides a rigid support for the jaws.

Another object of this invention is to provide a socket wrench that is compact, easily manufactured, and composed of the minimum number of parts.

Other objects of this invention will become obvious upon reading the following specification in conjunction with the accompanying drawings wherein:

Fig. 1 is a cross-sectional, side elevational view of the adjustable socket wrench.

Fig. 2 is a side, elevational oblique view of the assembled wrench showing a handle in phantom.

Fig. 3 is a side elevational oblique, exploded view of the wrench.

Fig. 4 is a cross-sectional view taken along the plane IV—IV of Fig. 1.

Fig. 5 is a cross-sectional view taken along the plane V—V of Fig. 1.

Fig. 6 is a bottom view of the cap for the housing illustrating the eccentric cam means for locking the cap on the housing.

Fig. 7 is a cross-sectional view taken along the plane VII—VII of Fig. 6.

Fig. 8 is a bottom view of the assembled wrench.

Fig. 9 is a partial, cross-sectional view taken along the plane IX—IX of Fig. 1.

Briefly this invention relates to an adjustable socket wrench having a housing with a base and side walls. The base has a central opening and grooves extending radially outwardly from the opening. A plurality of jaws are

2

provided one for each of the grooves. Each of these jaws has a gripping nose extending downwardly through the opening in the base and a flange plate reciprocally mounted in the housing with a ridge extending from the bottom of the plate and seated in one of the grooves. The jaws are actuated by a cammed plate having cam shaped openings receiving pins extending upwardly from the jaw plates.

In accordance with one aspect of this invention, I enclose the entire jaws except for the nose portion extending downwardly from the housing. The housing has a base, a top and side walls. The jaw and nose extend through the base and the flange portion of the jaw is mounted to slide radially on the base inside the housing. A cammed means is operatively connected to the flange portion of the jaw for engaging the same and positioning the jaws after they are placed over the nut. The housing has slots in the side walls through which handles extend for actuating the cammed means.

Referring to the drawings, reference numeral 1 denotes the assembled socket wrench including an enclosed housing composed of the cup shaped shell 10 enclosed at its open top end by the cap 20. The housing contains the jaws 30 and the cam plate 40.

The shell 10 has side walls 11 and a base 12. The side walls 11 are threaded at the top end for receiving the cap 20. The walls 11 have two slots 14 each extending partially around the shell and a groove 15 (Fig. 9) receiving an eccentric cam 24 that locks the cap 20 on the shell.

Base 12 has a central opening 16 from which radiate the slots 17 (Figs. 5 and 8). Projecting radially from the outer end of the slots 17 are the grooves 18 on the inner face of the base 12 (Fig. 5). The slots 17 and grooves 18 are adapted to receive the jaws 30.

The jaws 30 are composed of two parts, the gripping nose 31 and a flange plate 32 connected together by the shank 33. The nose is any shape that provides the proper nut contact surfaces 34. The flange plates 32 which are slidably mounted in the housing are pie-shaped. Each of these flange plates has ridges 35 extending downwardly into the grooves 18 of the base 12. The grooves thus provide tracks for the flange plate and prevent the jaws from turning. The flange plates 32 also have a pin 36 extending upwardly and providing a means for camming the jaws toward and away from each other as will be explained hereinafter. The jaws are constructed of steel similar to that used in any type of socket wrench.

The cam plate 40 is a circular disc having the cam slots 41 receiving the pins 36 of the jaws 30. These cam slots are arranged so that upon rotation of the cam plate the jaws are made to grip the nut. The cam plate has the wing pins 42 extending from its peripheral side through the elongated slots 14 in the shell side walls 11. Secured to the wing pins 42 and riding on the outside of the shell pin are the arcuate plates or handles 43. Preferably these handles are serrated or knurled for facilitating easier gripping of them. This structure provides a means whereby the cam plate can be rotated exteriorly of the entire enclosed housing.

The cap 20 has a threaded portion 21 engaging the threaded portion 13 of the side walls 11. It has a central opening 22 forming a socket for receiving a handle 50 as illustrated in phantom by Fig. 2. The cap 20 has a ridge 23 protruding downwardly and just barely engaging the cam plate 40. It is important that the ridge 23 does not exert frictional force on the cam plate to prevent the cam plate from turning. In fact, it frequently proves advisable to space the ridge 23 just a very slight distance from the cam plate 40 to limit the upward movement of the cam plate.

Rotation of the cap with respect to the housing is prevented by an eccentric cam 24 (Figs. 1, 6, 7 and 9) attached to the end of the pin 25 which has a slotted head 26. The eccentric cam is thus rotatable from the top of the cap by means of a screw driver or any other suitable tool.

Assembly

This socket wrench is easily assembled. The jaws 30 are first inserted through the aperture 16 of the base 12. When properly positioned the noses 31 of the jaws extend downwardly and the ridges 35 ride in the grooves 18 of the base 12.

After the jaws are located in the shell 10 the cam plate 40 is inserted in the shell so that the pins 36 of the jaws are received in the cam slots 41. The wing pins 42 are then inserted through slots 14 and attached to the sides of the cam plate 40. Then the arcuate plates or handles 43 are attached to the pins 42.

The cap 20 is threaded into the open end of the shell 10 until the ridge 23 barely touches the cam plate 40. I prefer to then back up the cap 20 a half turn leaving sufficient clearance between the ridge 23 and cam plate 40 so that there is no binding. The ridge 23 then merely limits the upward movement of the cam plate. After the cap is inserted care is taken that the eccentric cam 24 is aligned with the groove 15 in the side wall. Then the pin 25 is turned by a screw driver or other tool. This locks the cap 20 to the shell and prevents relative movement between the two elements. The socket wrench is then ready for use.

Operation

The wrench is easily operated by first adjusting the jaws to fully open position by means of turning the handles 43 in the proper direction. Then the socket wrench is inserted over the nut or bolt head and the handles are rotated in the opposite direction causing the jaws to firmly grip the nut. Then the handle 50 shown in phantom in Fig. 2 is inserted into the socket or central opening 22 of cap 20. The handle is rotated causing the wrench to rotate and loosen or tighten the nut.

It should be evident from the above description that I have provided an adjustable socket wrench that is easily adjustable and is rigid and strong. The entire mechanism is enclosed in a housing which rigidly supports the jaws and prevents turning of the same. The unit is compact and constructed of a minimum number of parts. Therefore, the manufacturing cost is relatively low as compared to many adjustable type socket wrenches heretofore proposed.

Having described my invention it should be obvious that alterations or modifications thereof are possible within its broadest aspect. These alterations and modifications are considered to be covered by this invention unless the appended claims by their language expressly state otherwise.

I claim:

1. A wrench comprising a housing having a base and side walls; said base having a central opening and guide grooves extending radially outwardly from said opening; a plurality of jaws, one for each of said grooves, said jaws each having a gripping nose extending downwardly through said opening and a flange plate laterally, slidably mounted in said housing; a ridge extending from the bottom of each of said flange plates and slidably seated in one of said grooves; a pin extending upwardly from each of said flange plates; a rotary cam plate having cam shaped openings each receiving one of said pins; and means for rotating said cam plate.

2. A wrench comprising a housing having a base and side walls; said base having a central opening and guide

grooves extending radially outwardly from said opening; a plurality of jaws, one for each of said grooves, said jaws each having a gripping nose extending downwardly through said opening and a flange plate laterally, slidably mounted in said housing; a ridge extending from the bottom of each of said flange plates and slidably seated in one of said grooves; a pin extending upwardly from each of said flange plates; a rotary cam plate having cam shaped openings each receiving one of said pins; and at least one handle extending radially from the peripheral side of said cam plate through an opening in said side walls.

3. A wrench comprising a housing having a base and side walls; said base having a central opening and guide grooves extending radially outwardly from said opening; a plurality of jaws, one for each of said grooves, said jaws each having a gripping nose extending downwardly through said opening and a flange plate laterally, slidably mounted in said housing; a ridge extending from the bottom of each of said flange plates and slidably seated in one of said grooves; a pin extending upwardly from each of said flange plates; a rotary cam plate having cam shaped openings each receiving one of said pins; a cover on the top of said housing, a central opening in said cover providing a socket for a handle; and at least one handle extending radially from the peripheral side of said cam plate through an opening in said side walls.

30 4. A socket wrench comprising: a housing having a base, a top, and side walls therebetween; a plurality of jaws each having a nose portion and a flange portion; said base having an opening through which said nose portion extends, said flange portion being radially, slidably mounted in said housing on said base; rotary cam 35 means located between said top and the flange portion of said jaws and engaging said flange portion for positioning the jaws; said housing having at least one opening in the side walls; handle means operatively secured to said rotary cam means and extending through said side wall opening for exteriorly adjusting the jaws; and said top having a central opening providing a socket for a handle.

45 5. A socket wrench comprising a housing having a base, a top, and side walls therebetween; a plurality of jaws each having a nose portion and a flange portion; said base having an opening through which said nose portion extends, said flange portion being radially, slidably mounted in said housing on said base; cam means 50 located between said top and the flange portion of said jaws and engaging said flange portion for positioning the jaws; said top and said side walls having threaded portions engaging each other; said top having a central opening providing a socket, said socket adapted to receive a handle; and an eccentric friction cam element 55 mounted between said threaded portions and providing a locking means to prevent relative movement between said top and side walls.
